Inventor:
Alfred J. Thomas,
by Walter E. Lombard, Atty.

UNITED STATES PATENT OFFICE.

ALFRED J. THOMAS, OF BRAINTREE, MASSACHUSETTS.

DEVICE FOR SECURING CORDED TAPE TO EDGES OF SHOE UPPERS.

Application filed August 20, 1923. Serial No. 658,320.

To all whom it may concern:

Be it known that I, ALFRED J. THOMAS, a citizen of the United States of America, and a resident of Braintree, in the county 5 of Norfolk and State of Massachusetts, have invented certain new and useful Improvements in Devices for Securing Corded Tape to Edges of Shoe Uppers, of which the following is a specification.

10 This invention relates to devices for applying a corded tape to the edge of shoe uppers and the like, and has for its object the production of mechanism in which a tape and cord may be simultaneously fed to a folding 15 device in which a narrow strip of the tape may be folded over the cord onto a wider portion of the tape and secured thereto by a row of stitches, which stitches at the same time will unite the tape to said upper.

20 The invention consists of a guide having mounted thereon an arm having an opening therethrough for the passage of the tape, and another passage inclined thereto for the passage of the cord to be enclosed in a fold 25 at one edge of said tape, said guide being combined with a support through which the folded tape with cord enclosed at one edge thereof, is fed into a position beneath the needle of a sewing machine.

30 The invention further consists in means for adjusting said support and guide to accommodate them to different widths of tape.

The invention further consists in means whereby said guide may be moved out of 35 alignment with said support to facilitate the insertion of said tape and cord, first in said guide and then through the opening in said support.

40 The invention further consists of certain novel features of construction and arrangement of parts which will be understood readily by reference to the description of the drawings and to the claims to be hereinafter given.

45 For the purpose of illustrating the invention, one preferred form thereof is shown in the drawings, this form having been found to give satisfactory and reliable results, although it is to be understood that the various 50 instrumentalities of which the invention consists can be variously arranged and organized, and that the invention is not limited to the precise arrangement and organization of

the instrumentalities as herein shown and described, except as required by the scope 55 of the appended claims.

Of the drawings:

Figure 1 represents a sectional plan of a portion of a sewing machine having applied thereto an attachment embodying the principles of the present invention.

Figure 2 represents a side elevation of the same.

Figure 3 represents a side elevation of the 65 pivoted guide arm.

Figure 4 represents a horizontal section on line 4, 4 on Fig. 3.

Figure 5 represents a side elevation of the adjustable guide member.

Figure 6 represents a horizontal section on line 6, 6 on Fig. 5.

Figure 7 represents a horizontal section of the work support.

Figure 8 represents a vertical section on line 8, 8 on Fig. 7, and

Figures 9 to 12 inclusive represent sectional details of the successive positions of the tape and cord until secured to the upper.

Similar characters indicate like parts throughout the several figures of the drawings.

In the drawings, 10 is a cylindrical member or barrel, forming a part of a Singer sewing machine, provided with a reciprocating needle 11, a presser foot 12, and a feed foot 13, all of usual construction and forming no part of the present invention.

To the barrel 10 is secured a bracket 14, having pivoted thereto at 15 a guide formed in two parts 16, and 17, the part 17 being 90 adjustable relatively to the part 16.

The bracket 14 has a slot therein through which extend the clamping screws 18. By loosening the screws 18, the bracket 14 may be adjusted horizontally and then secured in adjusted position by turning said clamp screws.

The guide member 16 has a slot 19 therein concentric to the pivot 15, through which extends a clamp screw 20 to retain said 100 member 16 normally in raised position.

By loosening the screw 20, the member 16 may be moved downwardly about its pivot 15, for the purpose to be hereinafter described.

This member 16 has a lateral flange 21

at its outer end and a tape-receiving opening 22 extending therethrough.

The part 17 of the guide has a tube 23 extending therethrough, the projecting end 5 of which is positioned in the opening 22 and is inclined toward the outer wall thereof.

The tube 23 is adapted to receive a cord 24, which is to be enclosed within a fold 10 25 of a tape 26.

This member 17 has its outer end wall 27 so shaped in conformity with the inner wall of the flange 21 that a curved passage will be formed into which the tape 26 is adapted 15 to be fed.

The opposite end of the member 17 is provided with a slot 28 in which are positioned the headed screws 29 threaded to the member 16.

20 By loosening the screws 29, the member 17 may be adjusted relatively to the member 16 so as to accommodate the passage in the guide 16, 17 to different widths of tape 26.

As the tape 26 is fed through the passage 25 in the guide 16, 17, a narrow portion 30 thereof will be folded over to form the fold 25, and as the cord 24 is being fed simultaneously toward this fold 25, it will be positioned in said fold 25 as the tape 30 26 moves outwardly from the opposite end of said guide passage.

The bracket 14 has a lateral shelf to which is secured a work support 31 consisting of a U-shaped plate, beneath which is disposed a plate 32 having slots 32* in the inner end thereof, through which slots extend the headed screws 33 for securing the U-shaped plate to the bracket 14. The inner end of the plate 32 is provided 40 with a flange 33* by which the plate 32 may be adjusted relatively to the U-shaped plate 31 when the screws 33 are loosened.

The outer end of the plate 32 forms, with the inner wall of the U-shaped bend of 45 plate 31, a slot 34 through which the folded tape 26, with the cord 24 in its fold 25, is fed toward the needle 11, which is adapted to unite the edge of the folded portion 30 to the body portion of the tape 26, with 50 the cord 24 in the fold 25 thereof.

Simultaneously with the feeding of the tape 26 and cord 24, an upper 35 of a shoe is fed toward the needle 11, while resting, inside up, upon the upper face of the U-shaped member or work support 31.

Consequently, the same stitches which unite the fold 25 to the body portion of the tape 26 at the same time unite the tape 26 to the edge of the upper 35.

60 The edge of the upper 35 while feeding, bears against a shoulder 36 on a gage 37, adjustably mounted on the barrel 10, so that the folded tape 26 is secured a uniform distance from the edge of the upper.

This gage 37 has a slot 38 in its opposite 65 end through which the clamping screws 39 extend into the barrel 10.

When at the beginning of the operation, it is necessary to insert the tape 26 into its passage in guide 16, 17, and the cord 24 70 into the tube 23, the member 16 is moved downwardly about its pivot 15 so that the passage and tube will be out of alinement with the slot 34 in the work support 31, thus facilitating the insertion of the tape 75 26 and cord 24 and permitting the ends thereof to be pulled through the passages therefor.

After sufficient lengths of tape and cord have been pulled, through the guide 16, 17, 80 these ends are then inserted into the slot 34 in the work support 31, the member 16 being at this time in its lower position, giving free access to the slot 34 of the work support 31.

An opening 40 in the work support 31 is provided, through which a suitable tool may be inserted to assist in feeding the tape through the slot 34 in said work support 31.

The ends thus inserted are then positioned beneath the presser foot 12 and feed foot 13, and the subsequent operation of the sewing machine will then cause the tape 26 and cord 24 to be continuously drawn from the sources of supply. 95

By means of this mechanism, the tape 26 may be folded with a cord 24 in its fold 25, and then at one operation the folded portion may be secured to the body of the tape 26 and also to the upper 35. 100

A great saving in time is made by simultaneously performing all these operations, and a great advantage is gained inasmuch as no adhesive is required to retain the parts in position until the upper is finally 105 finished.

It is believed that the operation and many advantages of the invention will be understood readily without further description.

Having thus described my invention, I 110 claim:

1. In a device of the class described, a support having a transverse slot therein; a guide at one side of the entrance to the slot of said support having a tape-receiving opening therethrough normally in alinement with said slot, adapted to fold an edge of the tape while being fed therethrough into said slot, and a passage for a cord in said guide inclined toward said tape-receiving opening. 115

2. In a device of the class described, a support having a transverse slot therein; a guide at one side of the entrance to the slot of said support and separated therefrom, said guide having a tape-receiving opening therethrough normally in alinement with said slot adapted to fold an edge of the 120 125

tape while being fed therethrough into said slot; a passage for a cord in said guide inclined toward said tape-receiving opening; and means whereby said guide may be moved out of alinement with said slot.

3. In a device of the class described, a support having a transverse slot therein; a guide at one side of the entrance to the slot of said support and separated therefrom, 10 said guide having a tape-receiving opening therethrough normally in alinement with said slot adapted to fold an edge of the tape while being fed therethrough; and a tubular member in said guide forming a 15 passage for a cord in said guide inclined toward said tape-receiving opening.

4. In a device of the class described, a support having a transverse slot therein; and a guide pivotally mounted on one side 20 of said support and having extending therethrough a tape-receiving opening normally alined with said slot and a cord-receiving passage inclined toward said opening.

5. In a device of the class described, a support having a transverse slot therein; a guide pivotally mounted on one side of said support and having extending therethrough a tape-receiving opening normally alined with said slot and a cord-receiving passage 30 inclined toward said opening; and means for limiting the movement of said guide about its pivot.

6. In a device of the class described, the combination of a support consisting in part 35 of a flat plate; a U-shaped member mounted on the outer end thereof and forming, with the end of said plate, a slot, the parallel walls of said member contacting with the opposite faces of said plate; and a guide 40 secured to the side of said support and having passages therethrough nomally alined with said slot through which a tape and cord may be fed into said slot.

7. In a device of the class described, the 45 combination of a support consisting in part of a flat plate; a U-shaped member mounted on the outer end thereof and forming, with the end of said plate, a slot, the parallel walls of said member contacting with the 50 opposite faces of said plate; a guide secured

to the side of said support and having passages therethrough normally alined with said slot through which a tape and cord may be fed into said slot; and means whereby said plate may be adjusted relatively to 55 said U-shaped member to vary the size of said slot.

8. In a device of the class described, the combination of a support consisting in part 60 of a flat plate; a U-shaped member mounted on the outer end thereof and forming, with the end of said plate, a slot, the parallel walls of said member contacting with the opposite faces of said plate; and a guide secured to the side of said support and having 65 passages therethrough normally alined with said slot through which a tape and a cord may be fed into said slot, said guide being formed in two parts, adjustable relatively to each other.

9. In a device of the class described, a support having a tapered transverse slot therein; a guide at one side of the entrance to the slot of said support having a tape-receiving opening therethrough normally alined 70 with said slot, adapted to fold an edge of the tape while being fed therethrough, and a passage for a cord in said guide inclined toward said tape-receiving opening.

10. In a device of the class described, a support having a transverse slot therein; a guide at one side of the entrance to the slot of said support having a tape-receiving opening therethrough normally alined with 75 said slot, provided at its outer end with a curved projecting flange and adapted to fold an edge of the tape while being fed therethrough; a passage for a cord in said guide inclined toward said tape-receiving 80 opening; and means whereby said guide may be moved out of alinement with said slot.

Signed by me at 746 Old South Bldg., Boston, Mass., this 17th day of August, 95 1923.

ALFRED J. THOMAS.
